(57) CLAIM

I claim the ornamental design for a card holder for a portable device, as shown and described.

DESCRIPTION

FIG. 1 shows a left side view a card holder according to the invention;

FIG. 2 shows a top view of the holder;

FIG. 3 shows a bottom view of the holder;

FIG. 4 shows a front side view of the holder;

FIG. 5 shows a right side view of the holder; and,

FIG. 6 shows a back side view of the holder.

The broken lines showing a backplate, opening and slots are for the purposes of illustrating environment and forms no part of the claimed design.
